TWO-WIRE, TWO-WAY, LOCAL-CENTRAL
STATION TRANSMISSION SYSTEM

Arthur W. Donelson, Flint, Mich.

Application June 6, 1942, Serial No. 446,128

11 Claims. (Cl. 179—6)

This invention relates to a two-way electrical system between a central station and a local station, the central station being operatively associated with a plurality of local stations, the number being determinable solely by the number of central station operators and equipment, one central station operator usually being utilized in connection with a plurality of local stations.

A system of this general character now in commercial use is commonly known as the automatic hostess phonograph system, although the central station program supplied to the local stations need not be of phonograph reproduced type.

Such systems require four transmission wires connecting each local station to said central stations.

The chief object of the present invention is to reduce the number of wires required between each local station and the central station.

Such reduction naturally is less costly to install and operate, whether the wires be owned or leased. Further such wire number reductions reduces the possible number of circuit variables with all the attendant advantages.

The chief feature of the present invention is to provide in a system of the aforesaid general character but two wires between the central station and the local station and to utilize at both stations certain arrangements which permit satisfactory utilization of such two wires, such arrangements being mutually cooperative.

For a better understanding of the present invention some general description is believed in order, and referring to such hostess system, at each local station, there is a music reproducing arrangement which has one or more coin receivers. At each coin receiving station there is included a switch that closes a circuit when the proper coin has been deposited and has been acknowledged to be proper if a coin selector is utilized and the circuit so completed includes a coin controlled coil relay.

To keep a financial record of the amount of money deposited at any one local station there is associated with the singular pair of lines in the central station a personal coin counter circuit which includes a conventional coin counter relay that controls a switch in a circuit to a counting device which may be of any one of the conventional types now known. The coin operable relay at the local station when actuated thus registers coin deposition in the central station.

The central station operator then depresses the operator's key in the proper circuit and requests the depositor to designate the desired program

number. Then the desired program is supplied to the circuit and reproduced at the reproducer at the local station.

The present invention is so arranged that the depositor's request is not reproduced at the local station nor is the program reproduced at the central station. This invention, therefore, eliminates the aforesaid undesirable features.

The full nature of the invention will be understood from the accompanying drawing and the following description and claims:

In the drawing,

Fig. 1 is a diagrammatic illustration of the invention, the coin receiving station structure, slug ejector, coin registering or counting device being omitted for clearness and only such portions of the several output and input arrangements being shown as is necessary for an understanding of the invention since the remainder of such arrangements are of conventional character.

Fig. 2 is a diagram of a modification of a portion of the local station circuits as hereinafter specified.

Fig. 3 is a diagram of a modification of a portion of the central station circuits as hereinafter specified.

Before proceeding with a detailed description of the invention reference will first be had to the coin controlled circuit and the coin registering circuit. In the drawing A and B designate two lines between a local station and a central station. At the local station there is included at least one coin operable switch diagrammatically in series with a coin operable relay 10, the movable portion 10a of which is associated with certain switches.

At the central station is a counting device, not shown, that is electrically operable, the supply to the operating circuit therefor also being omitted, said circuit including line 13 and a switch 12 operable by a relay 11 having movable portion 11a. The switch 12 includes stationary contact 12b and movable contact 12a both in the circuit including line 13. Switch 12 is normally open. When closed by member 11a in response to relay 11 energization, the coin register is actuated.

Relay 11 is connected by line 19 to line A. It is also connected to line B by line 20. Across the relay 11 and in multiple therewith there may be included the resistor R and in series with the condenser 22 for reducing or limiting cross talk.

The coin controlled relay 10 moves member

10a. Associated therewith are three switches designated by numerals 14, 15 and 16.

The switch 14 is a member responsive to coin relay 10 and it is normally in contact with switch point 14a for closing the line A. The switch 15 is normally in contact with the switch point 15a for normally closing the line B. There is a pair of supplementary supply lines 17 and 18 connected to a low voltage supply, herein 25 volts A. C. Line 17 therefrom leads to a switch point 17a while line 18 leads to a switch point 18a. When the coin relay 10 is energized by coin deposition, the switch points 14 and 15 are moved by member 10a from the contacts 14a and 15a, respectively, to engage the contacts 17a and 18a, respectively, thereby supplying voltage to the lines A and B from the local station to the central station including lines 19 and 20, before mentioned, for coin registration at the central station.

When the coin is deposited at the local station and by reason of energization of coil 11 by the current supplied from lines 17 and 18, the switch member 12a moves to contact contact 12b. It will be noted this central station switch 12 is normally open and is only closed when the coin is deposited at the local station. The counting device thereupon is energized by the circuit connected thereto and controlled by this switch 12, which counting device is at the central station so that the central station has a financial record of the coins deposited at the local station and the central station operator also knows a depositor is entitled to program preference.

At the local station there is provided a microphone preamplifier output transformer 23 which couples the output of the microphone preamplifier to alternate legs of a Wheatstone bridge. There is also a transformer 24 which couples the other alternate terminals of the Wheatstone bridge to the input of the program amplifier.

The Wheatstone bridge includes either two 500 ohms resistances and 1,000 ohms potentiometer or two 1,000 ohms potentiometers which are arranged so that they are balanced. This Wheatstone bridge arrangement includes a leg W and a leg X. The line B is connected to the junction or terminal of legs W and X at 25. Across the leg X is interposed a condenser 26, the value of which is unknown and is determined by experiment. This is fundamentally determined by the dielectric capacity of the two lines to which it is connected.

The third leg of the bridge is designated by Y and the fourth leg by Z. The junction 27 of these two legs is connected by line 28 to one end of the secondary 23b of the transformer 23. The other end of this secondary is connected by the line 29 to the line B. The line A connects at 30 to the leg W. The line 31 from the leg X connects to the other end of the leg Z. The line 32 from the other end of leg Y connects to the line A at 33. The line A is connected at 33 by line 33 to one terminal of the primary 24a of the program input transformer 24. The other terminal thereof is connected by line 34 to the leg Z and line 31 at 35 as illustrated.

In addition to the foregoing, a line 35 is connected at 36 to the line 28 and it includes the coin operable movable switch member 16, before mentioned. Associated therewith is a stationary contact 16a which is connected by the line 36 to line B at 37 on the side of switch 15 remote from the central station. When the coin is deposited insofar as switch 16 is concerned, switch

member 16 closes a circuit from line B if switch 15 contacts contact 15a and the effect of the closing of switch 16 is to short out the secondary of the transformer 23. The relationship of the several switches 14-15-16 is as follows:

Switch member 16 must make contact with contact 16a before switch members 14 and 15 break from contacts 14a and 15a, respectively. In returning to normal the switch member 16 must break contact from 16a after switch points 14 and 15 have made contact with contacts 14a and 15a, respectively. The reason for this stipulation is that unbalance caused by the removal of lines shall not cause acoustic feed back which is accomplished by interrupting the continuity of the path of possible acoustic feed back, or oscillation.

The foregoing constitutes a description of substantially all that is found and required at the local station, and the local station registration in the central office or station.

At the central station there is provided a transformer 40 which has its secondary 40b connected to the operator's receiver input arrangement including a tube 79 with a grid 79a. There is also provided at the central station another transformer 41, the primary 41a of which is connected to the program output and the operator's microphone output arrangement, including a tube 60 with a plate 60a. The line A connects at 42 to one terminal of the primary 40a of the transformer 40. The line B connects at 43 to one terminal of the secondary 41b of the transformer 41.

The transformer 41 is substantially the output transformer of the program preamplifier. Transformer 40 is the input transformer of the operator's receiver amplifier.

Line 44 leads from the other terminal 45 of the secondary 41b of the transformer 41 to one leg, designated by the letter M, of the Wheatstone bridge at the central station. The latter leg in turn is connected as at 46 to the line A. The other terminal 47 of the primary 40a of the transformer 40 is connected by line 48 to a leg N of the bridge at the central station, the other end of that leg being connected by line 49 to the line B at 50. A third leg P of the bridge at the central station is connected at 51 to the line 42 and at 52 to the line 44.

It will be noted that as illustrated the Wheatstone bridge, at the central station, has but three legs thereof located at that station. The fourth leg of this bridge in this instance, is the leg W at the local station. If desired, the leg W may be connected across lines A and B at the central station and in that event leg W would be omitted at the local station.

A further modification would be to have the leg W twice the value of its original value and located at the local station as shown and another leg of the same value, that is twice the value of the leg W, at the central station, the latter leg then being connected across the lines A and B. The resulting effect, since these two legs are in parallel, would be that these two legs, although each are of double value, in electrical effect would have the same value as the singular leg W positioned at either the local station or the central station.

It is believed with this description no illustration of these two modifications is required.

In this connection it is to be observed that the same precaution as to values with regards the central station legs M, N and P must be observed that have been mentioned in connection

with the values of the local station legs W, X, Y and Z. In other words, balance must be maintained.

In this connection it is also to be noted the contact 25 between the legs W and X is intentionally made variable to compensate for the resistance of lines A and B which may vary.

Operation

Any modulation appearing across the secondary 23a of transformer 23 appears across points 25 and 27 of the Wheatstone bridge at the local station and since the bridge is balanced this modulation will not appear across the primary 24a of transformer 24 which is connected between points 30 and 39. The modulation, however, will appear across leg W and be conveyed by means of lines A and B to points 46 and 50 whereupon said modulation will occur in both transformers 40 and 41.

The modulation set up in the secondary 41b of transformer 41 will be to no avail for the primary 41a thereof connects to the plate 60a of the tube 60 which is unresponsive to this modulation. However, the modulation set up in the primary 40a of transformer 40 will appear in the secondary 40b thereof and effect the grid 70a of tube 70, thereby conveying the modulation from the microphone preamplifier output at the local station to the operator's receiver input.

In a like manner, modulation introduced into the primary 41a of transformer 41 by the plate 60a of tube 60 will appear in secondary 41b and in leg N between points 52 and 53, same being alternate leg terminals. This modulation is not received at points 46 and 51, the other alternate leg terminals of the central station bridge, due to the balance of this circuit, but that modulation is conveyed by lines A and B to points 33 and 25 across one leg W of the local station bridge, which is conveyed to the circuit, as illustrated, to the secondary 23b of transformer 23 and to the primary 24a of transformer 24.

The modulation thus introduced into the primary 23a of transformer 23 is of no avail for it appears on the plate 80a of tube 80, which is unresponsive to such modulation. The modulation occurring across the primary 24a of transformer 24 appears in secondary 24b thereof and effects the grid 90a of tube 90 causing the signal or modulation which was introduced from the plate 60a of tube 60 at the central station to be introduced into the program amplifier at the local station.

It will be noted that any modulation or signal introduced into the system from the tube 80 is not reproduced by the tube 60 but is reproduced by the tube 70 and it will also be noted that any signal, etc., introduced by the tube 80 is not reproduced through the tube 90.

In like manner any signal introduced by the tube 60 is not reproduced by the tube 80 but is reproduced by the tube 90 and similarly, that signal introduced by the tube 60 is not reproduced by the tube 70.

It will further be observed that the circuit provided by the two lines A and B between the local station and the central station is controlled by the coin controlled switch arrangement so that at a certain interval the program necessarily is interrupted. This interruption is occasioned by the deposition of the coin. When the coin is freed and the coin switch returns to normal position, the program circuit is automatically reestablished. Merely for convenience,

the switch 16 is illustrated in the position or rather location shown, because it may be introduced at other points in the circuit to render either the microphone amplifier circuit or the program amplifier circuit inoperative for the purpose set forth, to-wit, elimination of oscillation or feed back.

Referring to Fig. 2 and Fig. 1, note that between points 25 and 30 of the latter there may be connected in multiple with leg X at the local station, a conventional impedance network designed to match the alternating current impedance imposed between points 25 and 30. In this case (Fig. 2) each resistance has a value of one-half the total of the line resistance, the condenser has a capacitance equal to the capacity between line wires A and B and the inductance shown in Fig. 2 electrically matches that of relay 11 winding—see Fig. 1. The purpose of the aforesaid is to maintain balance through the audio spectrum.

Referring to Fig. 3 and Fig. 1 note that between points 46 and 50 there may be included in place of or in multiple with leg M or N at the central station a conventional impedance network designed to match the alternating current impedance imposed between points 46 and 50—see Fig. 1—the purpose of which is to maintain continuous balance throughout the audio spectrum. Note herein there is illustrated, compared with Fig. 2, an additional 500 ohm resistance. The other units have the values specified above relative to the units illustrated in Fig. 2.

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A system including a local station and a central station and but two wires therebetween, an operator's receiver input structure at the central station, including a tube with a grid therein, and an operator's microphone and program output structure at the central station, including a tube with a plate therein, said structures each including a transformer coupling to said wires, a Wheatstone bridge structure operatively interposed between said wires and structures, a program input structure at the local station, including a tube with a grid therein, a microphone preamplifying output structure at the local station, including a tube with a plate therein, said two last mentioned structures each including a transformer coupling to said wires, and a Wheatstone bridge structure operatively interposed between said wires and the two last mentioned transformer coupled structures, the legs of each bridge being balanced.

2. A system as defined by claim 1, characterized by one leg of one bridge serving as a leg of the other bridge and being positioned at one station.

3. A system as defined by claim 1, characterized by each bridge having a leg double the value of each of the other legs, the double valued legs being connected in multiple across the wires.

4. A circuit of the character described including a local station including a program input device and a microphone output device, a cen-

tral station including a program output device and an operator's receiving input device, a single pair of wires therebetween; and a Wheatstone bridge arrangement for each station.

5. A circuit of the character described including a local station including a program input device and a microphone output device, a central station including a program output device, and an operator's receiving input device, a single pair of wires therebetween; and a Wheatstone bridge arrangement for each station, said stations having a common leg.

6. A system as defined by claim 4, characterized by the addition of a coin registering device operating circuit at the central station, a local station coin controlled circuit, a supplementary source of energy supply, switch means at the local station arranged to open the pair wire connections to the local station structures and connect the pair of wires to the supplementary supply, and means at the central station responsive only to that supply and controlling the registering device operating circuit for operation upon coin deposition at the local station.

7. A system as defined by claim 4, characterized by the addition of a coin registering device operating circuit at the central station, a local station coin controlled circuit, a supplementary source of energy supply, switch means at the local station arranged to open the pair wire connections to the local station structures and connect the pair of wires to the supplementary supply, means at the central station responsive only to that supply and controlling the registering device operating circuit for operation upon coin deposition at the local station, a transformer coupling each device across the wires, a normally open circuit across one of the transformer couplings, and switch means in said last mentioned circuit for shorting out said coupling and responsive to coin controlled circuit operation and in predetermined timed relation to local station switch means operation.

8. A system including at one station a primary and a secondary of two transformers, another station including a primary and a secondary of two other transformers, the primary at one station

being connected to the secondary at the other station, a pair of wires only between stations, a Wheatstone bridge at each station and operatively interposed between the wire connections to said transformers of said stations, one leg of each bridge being in series with one portion of a transformer at that station, said leg and transformer portion being across said wires, and an alternate leg of the same bridge being in series with the other portion of the other transformer at the same station, said alternate leg and other transformer other portion being across said wires.

9. A system as defined by claim 8, characterized by the addition of a coin registering device operating circuit at the central station, a local station coin controlled circuit, a supplementary source of energy supply, switch means at the local station arranged to open the pair wire connections to the local station structures and connect the pair of wires to the supplementary supply, and means at the central station responsive only to that supply and controlling the registering device operating circuit for operation upon coin deposition at the local station.

10. A system as defined by claim 8, characterized by the addition of a coin registering device operating circuit at the central station, a local station coin controlled circuit, a supplementary source of energy supply, switch means at the local station arranged to open the pair wire connections to the local station structures and connect the pair of wires to the supplementary supply, means at the central station responsive only to that supply and controlling the registering device operating circuit for operation upon coin deposition at the local station, a normally open circuit across one portion of a transformer and switch means in said last mentioned circuit for shorting out the last mentioned transformer portion and responsive to coin controlled circuit operation and in predetermined timed relation to local station switch means operation.

11. A system as defined by claim 8, characterized by one leg of one bridge serving as a leg of the other bridge and positioned at one station.

ARTHUR W. DONELSON
